UNITED STATES PATENT OFFICE.

FRED G. WALKER, OF CHICAGO, ILLINOIS, ASSIGNOR TO JONES SUPERIOR MACHINE COMPANY, OF CHICAGO, ILLINOIS, A CORPORATION OF ILLINOIS.

MEAT CUTTER.

1,427,661.

Specification of Letters Patent. Patented Aug. 29, 1922.

Application filed February 4, 1920. Serial No. 356,324.

To all whom it may concern:

Be it known that I, FRED G. WALKER, a citizen of the United States, residing at Chicago, in the county of Cook and State 5 of Illinois, have invented certain new and useful Improvements in Meat Cutters, of which the following is a specification.

10 which the following is a specification:
This invention relates to a machine for cutting meat or other analogous substances and is concerned chiefly with certain improvements in that type of machine which utilizes a saw or cutter in the form of a band that travels around upper and lower wheels suitably mounted in a framework.

15 An exemplification of my invention is illustrated in the accompanying drawings wherein—

Figure 1 is a side elevation;

Fig. 2 is an end view thereof;

20 Fig. 2 is an end view thereof;
Fig. 3 is a detail in elevation of the gauge;
Fig. 4 is an end view thereof;

Fig. 5 is a plan view of the scrip.

Fig. 5 is a plan view of the scraper, Fig. 6 is a side elevation thereof;

Fig. 6 is a side elevation thereof;

Fig. 7 is an end elevation of the 25 guide; and

Fig. 8 is a plan view thereof, and Fig. 9 is a side elevation thereof.

The framework of the present

The framework of the present machine is so constructed as to enclose most of its working parts, and, in the form shown, consists of a base 10 from which upstands a wall 11 bordered by a flange 12 which defines upper and lower chambers 13 and 14, respectively, connected by a passage 15, 35 which lies to one side of the machine. The wall 11 also extends laterally upon the side of the machine which is remote from the passage 15 to provide a bracket 16, and its flanges also extend around at points, such as 40 is denominated as 17, to form a partial enclosure which is completed by upper and lower doors 18 and 19 respectively, the former of which has a depending extension 20 and the latter an upstanding extension 21, 45 adapted to provide a closure for the passage 15. In the region of the center of this passage

15. In the region of the center of this passage is located a smaller door 22, in the form of a plate, but, if desired, this plate door may be formed as part of either extension 20 or 21 instead of as an independent

unit. Each door may be hinged to the framework by the usual ears 23 through which passes a pintle, and be provided with any suitable latch for remaining closed. In the drawing the upper and lower doors are 55 represented as open so as to exhibit the interior parts, the upper door 18 being preferably flanged on its inner sides as at 24 and carrying an angle bar 25 which depends therefrom in the manner best shown in 60 Fig. 2.

Within the framework so constructed are mounted upper and lower wheels 26 and 27 which are located respectively in the chambers 13 and 14, over which travels an endless band 28 which acts as a saw or cutter for the materials to be operated upon—usually meat in a machine of this kind. A motor 29 is carried laterally upon the frame in driving connection with the lower wheel 27, the upper wheel 26 being preferably adjustable toward and from the other as through the medium of a controlling handle 30 which co-operates with suitable means for this purpose. The band saw 28 passes through the flange 12 and between the upper and lower chambers 13 and 14, one part of the saw lying within the passage 15 and the other being exposed for operation. Depending from the upper portion of the machine in proximity to the exposed part of the saw is a rod 31 which carries at or near its lower end a laterally extending split sleeve 32 through which the band saw is required to pass, this sleeve housing two members 33 that lie upon opposite sides of the saw so as to keep its surface clean, and hold the saw steady in its movements. When the upper door 18 is closed the angle rod 25 lies adjacent the saw but on the side thereof which is opposite to the rod 31, the effect being to thereby constitute a guard that will protect the operator against injury from the saw, but which is removable with opening of the door.

A scraper for each wheel 26 and 27 is also provided, the construction whereof is best shown in Figs. 5 and 6. Each scraper is mounted interiorly of the framework in proximity to its associated wheel, and may 100

comprise a hub 35 from which extends a lug 36 having a flat surface on which is mounted a scraper element in the form of a blade or plate 37 slotted longitudinally as 5 at 38 to receive a bolt 39 whose shank is threaded into a suitable opening formed within the lug. The bolt head is suitably tightened upon the scraper blade to hold the same in any desired adjusted position, and 10 the device in its entirety may be mounted within the framework as by means of a bolt 40 which, in the case of the lower scraper, passes through the hub 35 to make threaded connection with the wall 11. The upper 15 scraper is preferably bolted to an arm 41 that extends from a plate 42 that is attached to the bearing in which the wheel 26 is mounted, this arrangement causing the scraper to move with the wheel when adjustments are effected through manipulation 20 of the handle 30. It will be noted that each scraper is adjustable relative to its associated wheel both angularly and longitudinally, the preferred adjustment being about 25 as indicated in Fig. 1 where the blade edge lies very close to the wheel.

The framework bracket 16 is used to support two spaced rails 43 adapted to receive the wheels 44 of a carriage 45 which receives the material to be operated upon. 30 This carriage travels close to the band saw, as shown in Fig. 1, and co-operates with a gauge which may take the form of a plate 46 having on its rear side a boss 47 that is 35 suitably socketed to receive the end of a bar 48, preferably square in cross section, the plate being thereby non-rotatably related to the bar. I have also provided an adjusting screw 49 rotatable through the 40 medium of a hand wheel 50 and having a swivel connection with the rear side of the plate 46, the screw co-operating with an arm 51 which has a fixed connection upon the bar 48, so that the plate may be moved 45 lengthwise of the bar as desired. Upon the door plate 22 is carried a box 52 through which is received the opposite end of the bar 48, a set-screw 53 being provided for holding the bar in any selected adjusted 50 position. It is apparent that the gauge may be set in any desired relation to the band saw either by manipulation of the set-screw 53 or by rotating the hand wheel 50, the latter, of course, effecting the finer adjustments, although through a smaller range. 55 As shown, the carriage presents an upper surface in the form of a table, preferably roughened or grooved to resist movement of the material carried thereon, a pan 54 being located preferably beneath the gauge for catching the slices of material that are severed from the part that is held on the carriage.

As it is desirable that the saw should be 60 guided and steadied as close as possible to

the place where its work is being performed, I have arranged a device for this purpose that will now be explained. Referring particularly to Figs. 7 to 9, the guide consists of a member having a base 55 that may be 70 bolted or otherwise secured to a part that supports the proximate rail 43; an upstanding web 56 which supports a fixed head 57 that is extended both laterally and longitudinally beyond the web; and a swinging 75 cap 58 which is hinged to the head as by means of a bolt 59, a thumb-screw 60 being suggested as a means for locking its swinging end in place. The cap is recessed as at 80 61 to accommodate a guide block 62 which may be secured to the head as by means of bolts 63, a second guide block 64 being secured to the other as by means of a bolt 65. A narrow space 66 for receiving the band saw is left between the two guide 85 blocks, which extends beyond their ends to the proximate face of the cap, the surrounding faces operating to guide and steady the band saw during movements thereof. As will be noted from the drawing, the head 90 and cap are offset to overhang beyond the base 56, so that the band saw may clear the member in its entirety. The construction just described is advantageous in that it accomplishes effectively the objects desired, and 95 may be readily opened up and disassembled whenever desired.

The machine just described should require no further explanation as to its operation which I have already made clear. It embodies the desirable features of a closure for the principal working parts, and of means arranged close to the material being acted upon, just above and below it, for holding the band saw to a steady course 100 of travel; a gauge that may be adjusted either fast or slow, and with great accuracy as well; a scraper for keeping each wheel clear of particles delivered to it from the band; and a general arrangement of the 105 several mechanisms such that there is an open space of appreciable magnitude between the upper and lower chambers wherein may be located such parts as the gauge and its adjusting mechanism and a catch pan 110 for receiving the sliced materials.

I claim:

1. In a machine of the kind described, the combination of a framework casing forming two connected and enclosed chambers, 120 a wheel in each chamber, a band saw extending around and between the two wheels and disposed in part in open space between the chambers, a door in the casing between the wheel chambers, and an adjustable saw 125 gauge mounted on the door adapted to be moved away from the saw when the door is opened, substantially as described.

2. In a machine of the kind described, the combination of a framework in the form of 130

a closed casing forming two connected chambers, a wheel in each chamber, a band saw extending around and between the two wheels with a portion of itself disposed in 5 open space between the two chambers, a swinging door in the casing between the wheel chambers, and a gauge mounted on

the door movable toward and from the exposed portion of the saw and adapted also to swing away therefrom when the door is 10 opened, substantially as described.

FRED G. WALKER.
